FREEWHEELING STOKER FAN

Ernest C. Webb, Bay Village, Ohio, assignor to
Iron Fireman Manufacturing Company, Port-
land, Oreg.

Application January 3, 1945, Serial No. 571,180

5 Claims. (Cl. 110—72)

1

This invention relates generally to stokers for solid fuel and particularly to a free wheeling stoker fan.

The main object of this invention is to provide a fan adapted to reduce off period smoking.

The second object is to produce a means for continuing the supply of air to a stoker or other fuel burning device for a period of time after the power supplied to the motor driving the air supply fan has been shut off.

The third object is to produce a fan of the class described in which the greatest supply of air is furnished at the shut-down period, after which a gradually diminishing supply is furnished.

I accomplish these and other objects in a manner set forth in the following specification as illustrated in the accompanying drawing, in which:

Fig. 1 is an end elevation of a stoker motor and a fan driven thereby.

Fig. 2 is a horizontal section through the coal hopper to disclose the coal worm in the bottom thereof.

Fig. 3 is a vertical section taken along the line 3—3 in Fig. 2.

Fig. 4 is a section taken along the line 4—4 in Fig. 3.

Similar numerals refer to similar parts throughout the several views.

Referring in detail to the drawing, there is shown a retort 10 of a stoker. To this retort coal or other solid fuel is carried through a coal tube 11 communicating with a hopper 12 by means of a coal feeding worm 13, driven from a transmission 14 by means of the motor 15, whose pulley 16 is connected by means of a belt 17 to the pulley 18 of the shaft 19, from which power flows to the transmission 14 through the gearing (not shown).

The shaft 19 is enclosed within a housing 20 which is integral with the motor supporting casting 21. The housing 20 is provided with a flange 22, to which is attached the fan guard 23. On the outer end 24 of the housing 20 is mounted an anti-friction bearing 25, which supports the streamlined fan hub 26. A cover plate 27 is mounted on the hub 26 and is used to keep foreign substances out of the bearing and insure the positioning of the parts. The hub 26 is provided with a cylindrical bore 28, in which is disposed an overrunning clutch element 29, which is keyed to the shaft portion 30 by means of the key 31. The element 29 is provided with wedge shaped recesses 32, in each of which is placed a

2

roller 33 which is free to rotate in one direction but will lock in the opposite direction.

The shaft 19 has its outer end 34 reduced to receive the anti-friction bearing 35, which supports the outer end of the member 26. Mounted on the hub 26 is a fan 36. The blades 37 of the fan 36 are supported at one end by the fly wheel 38. A ring guard 40 is provided around the exterior of the fan 36.

10 The operation of the device is as follows. Assuming that the stoker is being operated by the motor 15, that is, fuel is being delivered by means of the screw 13 and air is being delivered by means of the fan 36 under the driving action of the motor 15. With the present apparatus, if the motor 15 is stopped for any reason whatsoever, then the free wheeling action of the member 29 permits the fly wheel 38 to continue in its movement without being retarded by the motor 15, 20 and this continuing movement driving the fan 36 and supplying the necessary air to the combustion made possible by the volatiles driven off by the heat previously generated, that is, during the period of operation when a supply of air is especially needed, the fan, due to the inertia of its fly wheel 38, continues to supply a driving force to the fan after the worm 13 has ceased supplying fuel to the combustion, thereby bringing about a highly desirable condition in the combustion chamber.

25 While I have thus illustrated and described my invention, it is not my desire to be limited to the precise form shown herein, and I intend to cover such forms and modifications of the invention as fall fairly within the appended claims.

I claim.

30 1. In a fuel burner, the combination of a fuel conveyor, an air conveyor operatively associated therewith, said air conveyor comprising an impeller shaft and an impeller, a motor operatively connected with said fuel conveyor and said impeller shaft, and free wheeling means interposed between said impeller and said shaft whereby said air conveyor is adapted to operate after an operation by said fuel conveyor.

35 2. The automatic fuel burner of claim 1 characterized by said free wheeling fan having an inertia element attached thereto whereby said fan shall be caused to continue its rotation after said fuel conveyor has stopped.

40 3. In a stoker, the combination of a fuel delivery conveyor for moving fuel into a combustion zone, a motor for driving said conveyor, an air delivery fan driven by said motor for supply-

ing air to the combustion zone, a free wheeling clutch between said motor and said air delivery mechanism, and a fly wheel on said air delivery mechanism adapted to continue the rotation of said fan after the fuel delivery has ceased.

4. An automatic fuel burner comprising in combination a fuel feeding means, an air feeding means, said air feeding means including a rotary air impeller, a motor, said motor being operatively connected with said fuel feeding means to cause fuel to be fed to the combustion zone of said burner, and means operatively connecting said motor with said impeller to cause air to be fed to the combustion zone of said burner, said last mentioned means comprising an over-running clutch whereby said impeller may be positively driven by said motor in one direction of rotation only and whereby after said impeller has attained a certain speed in said one direction due to the driving action of said motor the motor speed may be reduced without thereby reducing the speed of said impeller in a proportional amount.

5. The automatic fuel burner of claim 1 characterized by having said impeller provided with an additional inertia element to store rotative

energy while said impeller is being driven by said motor in said one direction and to give up said energy to said impeller to aid in maintaining the rotative speed of said impeller when the driving force of said motor on said impeller is reduced.
